UNITED STATES PATENT OFFICE.

BENGT M. W. HANSON, OF HARTFORD, CONNECTICUT; EINAR A. HANSON AND CLARENCE E. WHITNEY EXECUTORS OF SAID BENGT M. W. HANSON, DECEASED.

METAL-WORKING MACHINE.

Application filed November 1, 1919. Serial No. 334,952.

To all whom it may concern:

Be it known that I, BENGT M. W. HANSON, a citizen of the United States, and a resident of Hartford, county of Hartford,

State of Connecticut, have invented certain new and useful Improvements in Metal-Working Machines, of which the following is a specification.

This invention relates to metal working machines and has particular reference to machines for shaping, contouring or otherwise machining or finishing curved surfaces.

As an instance of one use to which the machine forming the subject matter of this invention may be applied, reference may be had to the final finishing operation on a thread for the purpose of giving to that thread extreme accuracy in its shape, finish and size. In accordance with this invention, means are provided for bringing the work and the cutting tool into contact with extreme nicety both as to position and as to the amount of feed which would determine the amount of the cut to be taken. Also, the most accurate positioning of the tool to the work is provided for. Also means are provided for sharpening or resurfacing the tool without disturbing its relation to the work with the consequent advantage that after such sharpening operation the work and tool have the same relative relationship as when originally positioned, a feature which insures the greatest uniformity and accuracy and saving of time. There are also other features of novelty and advantage present in the machine to which reference will be made and which will be more particularly pointed out in the appended claims.

In the present disclosure of my invention, which is by way of illustration only and is not to be taken as restrictive of my conception, I show and describe my invention incorporated in a machine for grinding threaded members or the like and while the invention has peculiar adaptability for this use, I wish it clearly understood that it is not limited thereto, as it is susceptible of use in various operations upon members having concentric, eccentric or irregularly curved surfaces. Furthermore, while I have shown but one embodiment of my invention in the drawings, this showing is by way of exemplification only, the invention being

susceptible of various modifications and changes in construction and arrangement which would be within the spirit of the invention.

In the accompanying drawings:

Fig. 1 is a front view of the entire machine.

Fig. 2 is a left end view thereof.

Fig. 3 is a right end view thereof.

Fig. 4 is a plan view.

Fig. 5 is a sectional view taken substantially on line 5—5 of Fig. 4 and looking in the direction of the arrows.

Fig. 6 is a sectional view taken substantially on line 6—6 of Fig. 4 and looking in the direction of the arrows.

Fig. 7 is a plan view of the left hand end of the machine, some parts being in section and other parts being removed for purposes of clearness.

Fig. 8 is an elevational view of a ratchet clutch mechanism.

Fig. 8^a is a fragmentary view of certain parts thereof.

Fig. 9 is an elevational view of the ratchet clutch looking toward the right of Fig. 8.

Fig. 10 is a view of a work gauge, the trunion therefor being in section.

Fig. 11 is a vertical section through the gauge, the mounting therefor being in elevation.

Fig. 12 is a plan view of a truing device.

Fig. 13 is a sectional view thereof taken on line 13—13 of Fig. 12.

Fig. 14 is a front view of the truing device with parts thereof in section.

Fig. 15 is a sectional view taken on line 15—15 of Fig. 12.

Fig. 16 is a front elevation of the mounting for the grinding wheel shaft, and

Fig. 17 is an end view thereof.

Referring now to Figs. 1, 2, 3 and 4, the general arrangement and organization of the principal parts of the machine can be clearly seen. *a* is the pedestal or fixed bed, at either end thereof are fulcrums such as knife edges 5, 5, upon which the front of the rocking bed *b* is mounted. At the left hand end of this rocking bed there is a rearwardly extending arm *c* upon which a gear box *d* is mounted and with which is associated mechanism which will be herein-after described and by means of which this

rocking bed is rocked on its fulcrums.

By reference to Figs. 4, 5 and 6, it will be seen that the front of the rocking bed is of substantially the full width of the base and except for the rearwardly projecting arm *c*, it is relatively narrow but sufficient to provide lengthwise ways upon which the work holder, indicated generally at *f*, slides. This work holder comprises the main carriage *g* with which the lead screw *h* of the machine is engaged, a supplemental carriage *i* adjustable thereon and by which the position of the work relative to the work gauge and tool can be obtained and upon which the head and tail stocks *k*, *l*, are mounted, one of these, namely the tail stock *l*, being also adjustable. Of course, as will be understood, the work itself is supported between the head and tail stocks in the usual manner, and driven by the usual connection with the head stock spindle.

At the right hand end of the machine and rearwardly of the rocking bed and work holder mounted thereon is a slide *m* extending from front to rear of the machine and upon this slide is mounted the journal box *n* supporting the tool *t*, here shown as a grinding wheel.

From the foregoing description, it will be observed that the rocking bed has no movement relative to the pedestal except a rocking movement on its fulcrums, the knife edges 5, 5; that the complete work holder *f* slides longitudinally on the rocking bed moved by the lead screw *h*; and that the tool slide moves from front to rear of the machine but not longitudinally thereof, operated from the front of the machine by the hand wheel *o* or from the rear of the machine by the hand wheel *o'* either of which operates the screw *p* connected with the slide *m*. *u* is a feed shaft which may be operated either by the hand wheel *v* or automatically by mechanism indicated generally at *w* and which will be more particularly described hereafter.

It will be noted that the grinding wheel is solidly and rigidly supported on a fixed bed while the work is carried by a rocking bed mounted on knife edges. This arrangement is of the utmost importance in that it insures the greatest nicety in adjustment and maximum smoothness in operation, which means that very delicate grinding operations may be carried out with accuracy; vibrations, friction and other disturbing influences being reduced to a minimum or entirely eliminated. More particularly, the grinding wheel being mounted on a relatively heavy wheel slide, and the latter being securely clamped to and rigidly held at rest on the solid bed or pedestal, vibration of the wheel is practically eliminated. The grinding wheel is rotated at relatively high speeds which

necessitates the use of a belt. Owing to unevenness and irregularity in the belt, it has a tendency to set up vibrations in the grinding wheel shaft, but with the present arrangement, these vibrations are absorbed by the solid grinding wheel slide and the fixed bed, and thus the grinding wheel is held steady and will rotate smoothly and evenly, which would not be the case were the grinding wheel mounted for movement (other than rotary) during the grinding operation. The work spindle is driven at a relatively slow speed through a mechanical train of gears and, therefore, is not subjected to any excessive strains or stresses such as are exerted by a belt passing about a pulley. This means that the work holder may be mounted for movement on the rocking bed and the latter fulcrumed on knife edges, with the result that there is little or no friction at the fulcrum point of the rocking bed. This bed may be moved with great nicety permitting very delicate grinding operations, as where a fine relief is to be had on a threaded member, and smoothness in operation and accuracy in the finished product are obtained. The means for reciprocating the work holder and the various instrumentalities for rocking the rocking bed, together with the mechanism for controlling and driving the lead screw, work spindle and the rocking instrumentalities, are all mounted on the rocking bed. As herein-after described, the rocking bed is rocked through the means of a rocking beam pivoted on the bed, this arrangement being of advantage in that the various instrumentalities for rocking the bed may operate in the proper relation to one another to perform their desired functions and, owing to the fact that the rocking beam, in some instances, functions as a lever, the power required in rocking the bed, together with the parts thereon, is materially reduced.

I am aware that in certain cam grinding machines and gun stock lathes, a pivoted arm carrying the tool or fixed work support is provided but it is customary to journal such arm in a closed bearing, such as a sleeve, the result being that great difficulty is experienced in accurately fitting the arm and sleeve, and due to relatively large contacting surfaces, wear and friction therebetween will seriously interfere with the small and accurate fine adjustments essential in machines like that herein described. The feature of supporting the rocking bed on knife edges is of advantage in that the objections just noted are entirely overcome. With this arrangement the rocking bed may be positioned with the greatest accuracy, very fine feed adjustments are possible, and there is practically no friction or wear on the knife edges. The bearings for the knife edges 5 each

comprise a pair of blocks 201 and 202 which are clamped in place in a groove 200 in the rocking bed, or a part thereof, by means of plates 203 and screws 204. The faces of the blocks 201 and 202, before they are mounted in the groove 200, are ground by a suitable machine to substantially perfect planes. Thus, when the two blocks are fitted together, with the end of one block abutting a face of the other one, as shown in Fig. 6, two of the faces form a V-shaped groove which is adapted to receive the knife edge 5. This groove will have a very sharp apex at the bottom such as would be impractical to make in a single block. Thus, I find it more practical and economical to form the bearing of the two blocks 201 and 202 ground before being fitted together.

On the rear end of the rearwardly extending arm *c* of the rocking bed is a bracket 10 formed with a housing 11 within which is mounted a nut 12 to the lower end of which is keyed a worm wheel 13 in mesh with a worm 13^a, Fig. 7, at the end of the feed shaft *u*. This nut is free to slide through the worm wheel. 14 is a screw having threaded engagement with the nut, keyed to the housing as at 15 to prevent its rotation, and having a bearing at its lower end on a block 16 on the base of the machine. Supported in the upper end of the nut is a pin 17 which is preferably non-rotatable and engages the short end of a lever 20 which is fulcrumed on the bracket 10. For the purpose of describing the feed of the work to the tool when a new cut is to be taken, it may be considered that the lever 20 is an integral part of the bracket and has no motion relative thereto. It will be observed that this rocking bed, supported at the front on the knife edges 5, 5, is supported from the block 16 by the screw 14, nut 12, and pin 17 on which the lever 20 rests. Assuming now that the tool is free of the work and it is desired to take a new cut, the feed shaft *u* is turned so as to cause the nut 12 to travel down on the screw 14. This means that the distance between the block 16 and the lever 20 is decreased and as that decrease takes place, the rearwardly extending arm *c* drops slightly; the rocking bed rocking on the knife edges 5, 5, bringing the work near to the tool. For this feed, it is not necessary that the nut 12 shall be capable of sliding through the worm wheel 13, for the worm wheel, nut, pin 17 and lever 20 are, for all intents and purposes, fixed against longitudinal movement relative to the bracket 10 and rearwardly extending arms *c*. The nut, screw, pin, may be conveniently referred to as a variable connection forming part of the feed mechanism.

Assuming now that the tool has finished its cut and it is desired to return it to its

original position ready to take a new cut, it is advisable that the tool shall be free of the work during this reverse motion. In order to accomplish this, a cam 25 on the shaft 26, which is suitably driven as will be hereinafter described, comes into operation when the cut is finished and, acting on the long end of the lever 20, raises it. Since the short end of this lever is supported through the variable connection upon the fixed abutment block 16 which is on the pedestal of the machine, it will be obvious that, as the cam raises the long end of the lever 20, the bracket 10 and the rearwardly extending arm *c* are raised so that the rocking bed is rocked in a direction to move the work away from the tool. It is in this reversing action that the longitudinal movement of the nut 12 relative to the worm wheel 13 becomes necessary.

In a case where the contour of the work is irregular, as in the case of a tap which is relieved back of the cutting edge, a pattern disc 27 may be mounted on a shaft 28 suitably driven as will be hereinafter described, this pattern disc being shaped to correspond to the contour of the work which is being finished. It is engaged by a shoe 29 at the outer end of the lever 20. It will be apparent that, as the pattern disc is rotated, the lever 20 will be rocked about its fulcrum on the end of the pin 17 and raise and lower the rearwardly extending arm *c* which brings about a rocking of the rocking bed to and from the tool with the result that the tool is caused to operate on the work to produce a shape corresponding to the shape of the pattern disc and, of course, for this movement, the housing 11 must slide slightly up and down on the nut 12.

Whenever it is desired to put the pattern disc 27 out of action, this can be done by running down the screw 30 mounted in the lever 20 to engage the stop 31 and raise the lever just enough to clear the pattern disc 27 without raising the lever out of cooperative relation to the reversing cam. In this case the feed for the new cut and the reversing cam will be operative but the pattern disc will be inoperative. It will be seen that the contouring or shaping cam 27 is rendered ineffectual on the return stroke of the work holder, in the present instance it being rendered inoperative by separating the cam 27 from the rocking beam, the latter being raised and held out of engagement with the cam on the reverse stroke of the work by the lifting cam 25. This is of advantage in that chattering, noise and vibrations (which would result if the beam rested on the contouring cam while the work holder is being quickly moved on its return stroke) are obviated.

From a consideration of the foregoing description taken in connection with the illus-

tration of Fig. 6, it will be seen that this mechanism provides first for feeding the work to the tool for the purpose of taking out a cut or chip; second, for removing the work from the tool during the reverse stroke of the work for the tool because of backlash or lost motion in the driving connections will not properly cut the work on its reverse stroke; and third, that a piece of work having any irregular contour can be accurately and properly presented to the tool so that its entire surface can be accurately finished to the desired shape. It will, of course, be understood that by a proper timing all of this mechanism is brought into play in proper sequence.

The feed shaft *u* has at its front end a hand wheel *v* by means of which the work can be quickly raised or lowered into and out of engagement with the tool. Back of the hand wheel and mounted on this feed shaft *u* is the ratchet mechanism *w* controlled by the movement of the work holder *f* so that the work may be automatically fed towards the tool after each operative stroke of the holder. This ratchet mechanism may be of any suitable construction, that shown in the drawings comprising a ratchet wheel 34 fixed to the feed shaft *u* and a lever 35 pivoted on this shaft and carrying a pivoted pawl 36 cooperating with the teeth of the ratchet wheel. The lever 35 is connected, as shown in Fig. 1, by means of the link 37 with one end of a bell crank lever 38 fixed on a shaft 39, and the other arm of lever 38 is connected through a link 40 with a rocker 41 carrying a rod 42 which is actuated through the collars 43, 44, by a dog 45 on the work holder *f*. It will thus be obvious that, when the work holder *f* reaches the end of its operative stroke, the dog 45 engages the collar 43 on the rod 42 moving the rocker 41 and through described connections the ratchet mechanism *w* is actuated to turn the feed shaft *u* and thus permit the rocking bed to rock down slightly to take a new or deeper cut when a new cutting stroke is inaugurated. When the work holder *f* reaches the end of its reverse stroke, the dog 45 engages the collar 44 and through the connections described the pawl 36 will be moved back into its initial position, shown in Fig. 1.

The mechanism for the control and timing of the reversing cam 25, the pattern disc 27, the lead screw *h* and other operative parts is mounted on the rearwardly extending arm *c* of the rocking bed within the gear box *d*. Within this gear box, the shaft 26 carrying the reversing cam 25 and the shaft 28 carrying the pattern disc 27 are journaled. 50 designates a constantly rotating shaft journaled in the gear box and having a pulley 51 whereby it is driven. Fixed to the shaft 50 is a gear 52 meshing with a gear 53 nor-

mally running loose on the shaft 26. Between the gear 53 and a cam sleeve 54 fixed to the shaft 26 is a ratchet clutch mechanism, most clearly shown in Figs. 8, 8^a and 9.

Referring to these figures, 55 is a ratchet wheel fixed to the hub of the gear wheel 53, and 56 is a ratchet pawl pivoted to a flange or disc 58 carried by the sleeve 54. An escapement device controlled by the movement of the work carriage is employed to throw the pawl 56 into and out of engagement with the ratchet wheel 55 so as to intermittently rotate the reversing cam 25 one-half revolutions and operate a reverse clutch for the lead screw *h*.

This escapement mechanism is mounted upon a bracket 60 secured to the gear box *d* and has a pair of pivoted levers 61, the inner ends of which are diametrically disposed relative to the ratchet wheel 55. The outer ends of these escapement levers 61 are, by means of spring pressed plungers 62, maintained against opposed abutments 63 upon a vertically movable rod 64 connected at its lower end to a lever 65 affixed on the shaft 39 on which the crank lever 38, heretofore described, is also fixed. This shaft 39 is rocked when the dog 45 on the work holder *f* engages either of the collars 43, 44. With this arrangement, when the members are in the position shown in Fig. 8, the lower escapement lever 61 holds the pawl 56 out of engagement with the ratchet wheel 55 so that the shaft 26 is not rotated and the cam 25 is then in the position shown in Fig. 6. When the work holder reaches the end of its forward or cutting stroke the rod 42 is moved in a direction to rock the shaft 39, the rod 64 will be raised with the result that the lower lever 61 will release the pawl 56 permitting it to engage the teeth of the ratchet wheel 55; the shaft 26 together with the cam 25 will thereupon rotate until the pawl 56 is again thrown out of engagement with the ratchet teeth by the upper lever 61 the inner of which has been lowered into the path of the pawl. The cam 25 is thus turned 180° to raise the forward end of the rocking lever 20 and lift the work out of engagement with the tool. When the work carriage reaches the end of its reverse stroke, the shaft 39 will be rotated in the opposite direction, the rod 64 will be lowered, the inner end of the upper lever 61 will be raised to release the pawl, and the shaft 26 will rotate with the gear 53 until the lower escapement lever 61 trips the pawl 56 and the cam 25 is then again in the position shown in Fig. 6.

For the purpose of preventing the shaft 26 from rebounding when its rotation is stopped, a spring pressed plunger 67 carried by the bracket 60 is provided, and the disc 58 has notches into which the forward end of the plunger 67 engages at about the same

time as the pawl engages the escapement levers 61.

The mechanism for reversing the lead screw *h* is carried by the shaft 28 on which the pattern disc 27 is mounted. Referring to Fig. 7, upon this shaft is a pair of gears 70, 71. The gear 70 meshes with a gear 72 fixed on a shaft 50, and the other gear 71 meshes with a small pinion 73, fixed upon the stub shaft 74, having a gear 75 meshing with a gear 76 fixed to the shaft 50. It will thus be seen that the gears 70, 71 are constantly rotating in opposite directions. In the present instance the clutch mechanism, for connecting the gears 70, 71 with the shaft 28 is not shown in detail as the specific construction thereof forms no part of the present invention. It is sufficient to say that when a sleeve 77 slidably mounted upon the shaft 28 is moved to the left (referring to Fig. 7) the gear 70 will be fixed to the shaft and the gear 71 will run loose, and when this sleeve is moved to the right gear 71 is fixed and gear 70 is loose. Upon the outer end of the shaft 28 is a gear 78 driving a gear 79 fixed to a sleeve 80 to which the head stock spindle 81 is keyed. The lead screw *h* for the work holder is geared to the sleeve 80 through a gear 82 fixed to the sleeve 80; gear 83 meshing therewith; gear 84 fixed to the same shaft as is the gear 83; change gear 85, and gear 86 fixed to the lead screw *h* all of this gearing being similar to the common practice in an engine lathe.

The clutch mechanism just described is controlled by the ratchet clutch mechanism which is in turn controlled, as heretofore stated, by movement of the work carriage. The sleeve 54 fixed to the shaft 26 has a cam groove 90 in which works a pin carried by a shipper 91 having at its other end a pin working in a groove in the sleeve 77 of the reversing clutch mechanism. When the reverse clutch mechanism is in the position shown in Fig. 7 the gear 71 rotates with the shaft 28, and the shaft 50 drives the lead screw, through the gears 76, 75, 73, 71 and the train of gears leading from 78 to 86 in a direction to advance the work. When the work holder reaches the end of its forward stroke, the ratchet clutch mechanism is automatically thrown in so that the sleeve 54 is rotated through an angle of 180°, and the shipper lever 91 will be shifted to move the sleeve 77 of the reversing mechanism to the left whereupon the gear 70 will rotate with the shaft 28 and the lead screw will be rotated in the reverse direction through the gears 70—78, 79, etc. When the work holder *f* reaches the end of its reverse stroke the ratchet clutch mechanism shown in Figs. 8 and 9 is again actuated, shaft 26 rotates one half a revolution, and the cam groove 90 will shift the shipper 91 to fix the gear

71 to the shaft 26 and the reverse gear 70 65 will run loose.

The shipper lever 91 is fixed on a vertical shaft on the upper end of which is a handle 92 (see Fig. 4) whereby movement of the work may be instantly stopped when desired by throwing the clutch mechanism into neutral position, the cam groove 90 in the sleeve 54 being of increased width or offset as at 93 (see Fig. 7) so as to permit of this movement.

For the purpose of automatically stopping the work when it reaches the end of one of its strokes a lever 94 cooperating with the ratchet clutch mechanism is provided. The lever 94 is pivoted to the bracket 60 and at 80 its lower end is connected to a slide 95 which is normally out of the path of the pawl 56. When it is desired to stop the work, the slide 95 is moved into the path of the pawl, as shown in Fig. 8^a, and the sleeve 54 will 85 then be stopped in such position that the shipper 91 will have moved the sleeve 77 of the reverse clutch mechanism into neutral position, that is, where both the gears 70 and 71 will be running loose on the shaft 28. It will be seen that it is not necessary for the operator to wait until the work has reached the end of one of its strokes before stopping the machine, for it is merely necessary for him, at any desired time, to throw 95 the lever 94 into position so that the slide 95 will be in the path of the pawl 56 and the machine will then stop automatically at the end of its forward stroke, the operator in the meanwhile having his time free to attend to other matters.

97 is a constantly driven main shaft connected to the grinding wheel shaft 98 by means of a belt 99 so that the grinding wheel is also constantly driven. Passing about a pulley on the main shaft 97 and a pulley on a shaft 100 passing through the pedestal *a* is a belt 101. On the left end of this shaft 100 is a pulley 102 connected to the pulley 51 on the shaft 50 by means of a belt 103. A suitable idler 104 is provided to keep the belt 103 taut. It will be noted that the work holder including the spindle, the lead screw for moving the work holder, the various instrumentalities for rocking the bed, and the mechanism for driving and controlling all of these elements are located on the rocking bed. This driving mechanism is driven by a belt 103, the tendency of which is to hold the rocking bed to its fulcrums while at the same time permitting of substantially free rocking movement of the bed.

It being necessary to angularly adjust the grinding wheel in accordance with the lead of the thread to be ground, the journal box *n* in which the grinding wheel shaft 98 is journaled is mounted in a way 108 on the

slide *m* and the center of curvature of this way is the center of the wheel *t* by which is meant a point at the axis of the wheel which is included in a plane bisecting the angle of 5 the cutting edge of the wheel so that the axis about which the wheel may be angularly adjusted is on a line *a*—*a* (Fig. 5) intersecting the axis of rotation of the work. The journal box *n* is locked in adjusted position by means of bolts 109, the heads of 10 which work in undercut grooves 110 having the same center of curvature as has the way 108.

In briefly describing the operation of the 15 machine it will be assumed that the threads of a tap are to be ground. The tap is positioned between the head and tail stocks *k*, *l* and is so adjusted that its eccentric surfaces have the same relation to the grinding 20 wheel *t* as the corresponding surfaces on the pattern wheel 27 have to the rocking beam or lever 20. The work is then adjusted longitudinally so that the thread to be ground is in proper alinement with the grinding 25 wheel, and to get this adjustment the work gauge hereinafter described may be used to advantage. It will be seen that the extent to which the rocking bed may be swung on its fulcrums is limited to the distance which 30 the screw 14 can move relative to the nut or sleeve 12 of the variable feed connection and by other considerations, and therefore, the rocking bed will be adjusted with the view of allowing for further automatic 35 feeding of the work to the tool. The tool is then roughly moved up to the work by means of the handle wheel 10. If necessary, the feed shaft *u* is then manually turned in a direction to lower the pin 17 of the feeding mechanism until the rocking 40 bed has been swung downwardly and rearwardly into a position where the tool engages the work. In the event the handle 45 92 has been employed to stop the machine, this handle is swung to throw the shipper 91 of the reverse clutch mechanism and thus connect one of the gears 70 or 71 to the shaft 28 and the lever 94 of the ratchet clutch 50 mechanism is moved to permit actuation of the clutch mechanism and thereupon the head stock spindle 81 is rotated, and the lead screw *h* is driven. The pattern wheel 27 will impart an oscillating movement to 55 the rocking bed. As the work holder reaches the end of its cutting stroke the rod 42 is moved and thereupon the ratchet upon the feed shaft *u* will be given a partial rotation to move the work a step towards the 60 tool so that the tool may take a new cut. The movement of the rod 42 also actuates the escapement mechanism of the ratchet clutch so that the cam 25 is rotated one-half 65 a revolution in a direction to lift the rocking lever 20 sufficiently so that the work is held, on its reverse stroke, out of en-

gagement with the tool. At the same time, due to the half revolution of the shaft 26 and the cam sleeve 54 carried thereby, the reverse clutch mechanism in the train of gears leading to the lead screw *h* is operated 70 to reverse the work. When the work reaches the end of its reverse stroke, the rod 42 is moved in the opposite direction, resulting, through the escapement mechanism and the ratchet clutch, in another half revolution of the cam 25 so that the work will be lowered into engagement with the tool, and at the same time the reverse clutch mechanism is actuated so that the lead screw 75 is driven in a direction to advance the work. 80

I wish it to be clearly understood that a machine constructed in accordance with the present invention is not limited to a use wherein threaded members are machined. It is susceptible of use for various operations upon unthreaded members; for instance it may be employed to machine reamers, cams or other parts having concentrically or irregularly curved unthreaded surfaces. If a part having an unthreaded 85 cylindrical surface provided with portions in relief is to be ground, a grinding wheel having a relatively wide cylindrical grinding surface may be employed. Nor is the invention limited to grinding or other operations where it is customary to use a rotating tool, for a stationary tool of any desired shape may be employed for the purposes in hand. 95

Where a threaded piece of work is being 100 operated on and the operating tool is, for instance, a grinding wheel, it is extremely difficult to properly and accurately position the tool with respect to the work, mainly because of the large size of the grinding 105 wheel, its rough and uneven surface, and the relatively small size of the threads. In the present invention, I provide an improved gauge which is so constructed and arranged that the work can be quickly adjusted with the greatest accuracy and precision. 110

The construction of the work gauge is most clearly shown in Figs. 10 and 11 and its relation to the grinding wheel and the 115 truing device is most clearly shown in Fig. 5. The gauge is pivotally carried by a bracket 115 mounted on the front of the rocking bed *b*. The rocking bed *b* has a *T* slot 116 in which work the heads of bolts 117 passing through the bracket so that the bracket is adapted for rough adjustment relative to the tool holder. 120

The pointer 120 of the gauge is carried by 125 an arm 121 fixed, as most clearly shown in Fig. 10, to a pivot pin 122 trunnioned in bearings on the opposed ends of plungers 123, 124 mounted in sleeves 125 on the bracket 115. The plunger 123 may be adjusted longitudinally by a screw 126 and 130

behind the plunger 124 is a spring 127. The plungers may be clamped in adjusted position by turning set screws 128 down onto dogs engaging the plungers. With 5 this arrangement a fine adjustment of the gauge on a line parallel to the axis of the work may be had by turning the screw 126. The spring 127 serves to prevent any backlash or looseness between the bearings.

10 The forward end of the pointer 120 is preferably semi-conical so that the flat surface thereof, which is in a plane passing through the axis of the work, has true or sharp edges. The forward end of this flat 15 surface is of the same shape as the thread so as to closely fit therein. This pointer is carried by a slide 130 adjustable radially of the work within a barrel 131. Preferably the pointer 120 is surrounded by a 20 shield 132 having a top sight opening and immediately beneath the pointer is a source of illumination such as an electric light bulb 133. When adjusting the work and gauge relative to each other the operator 25 may, by looking down through the sight opening, determine when the pointer fits the thread.

In practice, to set the gauge relative to the 30 grinding wheel, a test piece, preferably unhardened and of any diameter but having the same number of threads to the inch as has the part to be finished, is positioned between the head and tail stocks and the threads thereon are ground. Then the 35 work gauge is thrown over into the full line position shown in Figs. 5 and 11. The gauge is adjusted to the test piece by rotating the screw 126 until the forward end of the pointer 120 accurately fits in the 40 thread. After the gauge is so adjusted, it is locked in position so that its relation to the grinding wheel *f* will remain fixed, but it may be thrown back into the dotted line position of Fig. 11 when not in use; the 45 test piece is taken out and the threaded member to be finished is substituted therefor; the gauge is then thrown forward and by adjusting the slide *g* by the screw shown the work is adjusted longitudinally until 50 the pointer accurately fits the thread thereof. As the work is now properly set to the gauge, the operator knows that it is in correct position relative to the grinding wheel for the gauge has already been set 55 to the wheel by using the test piece. As the gauge is carried by the rocking bed *b*, which has no rectilinear movement on the base *a*, and the tool or grinding wheel *t* is fixed to the base against movement longitudinally of the axis of the work, the 60 relative positions of the wheel and gauge remain fixed. Furthermore, as the gauge is carried by the rocking bed, the gauge and work move in unison to and from the 65 tool. After the work is properly adjusted

to the gauge, the gauge is thrown back into inoperative position and the grinding operation proceeded with. After the gauge is set for one part having a given number of threads per inch it may be employed to 70 accurately set any number of pieces having a like number of threads per inch, always with the knowledge that when the work is set properly to the gauge it will be in proper relation to the wheel. 75

A truing device for reshaping or resharpening the tool is provided which, in its construction and arrangement and relation to and combination with other parts of the machine permits of resharpening without disturbing the relation of the tool to the work and when once set to one face of the wheel will so operate on all faces as to generate a cutting edge which accurately conforms in shape and size to the thread which is being cut. The construction of this truing device will first be described, and then its relation to the tool and other parts will be pointed out.

Referring to Figs. 5 and 12-15 inclusive, 90 where the truing device is most clearly shown, 135 designates a bracket mounted upon the base of the machine and which, if desired, may be adjustable by sliding in a T slot 136 on the base *a* and is provided with means for securely locking it in position. Pivoted on a vertical pin 137 upstanding from this bracket is a carriage 138 which moves in a horizontal plane over a segmental plate 139 fixed at the top of the bracket 135. 140 is a horizontal shaft fitted in an upper part of the carriage with its axis at right angles to that of the vertical pin 137 about which the carriage turns. In other words, the vertical plane which includes the axis of this shaft 140 would also include the axis of the vertical pin 137. Mounted on the forward end of this shaft 140, is an arm 141 within which is positioned subject to longitudinal adjustment 95 on a line parallel to the axis of the shaft 140 the sharpening tool 142 shown as a diamond point which is well adapted for resurfacing such a tool as is here illustrated, 100 namely the grinding wheel *t*. In certain of the appended claims the arm 141 is referred to for convenience as the tool carrying part. On the shaft 140 is a worm wheel 148 with which meshes a worm 149 on a shaft 150 mounted in a suitable bearing in 105 the carriage and having at its outer end a hand wheel 151. The extent of rotation of the worm wheel 148 is limited by means of a fixed pin 153 extending into a notch 110 154 in the periphery of the worm wheel 148. Upon turning the wheel 151 in opposite directions the shaft 140 is turned and the diamond point will be oscillated back and forth across a face or edge of the grinding wheel which is being resurfaced. The 115 120 125 130

whole carriage may be swung around the pivotal pin 137 in order to bring the diamond point into operative relation with any face of the grinding wheel, and for the purpose of indexing it to the proper position and holding it there, the segmental plate 139 is notched as at 155 to receive a spring pressed plunger 156. Means for withdrawing the plunger from the notches 155 consists of an operating handle 157 on a rod 158 having at its lower end a lever 159 engaging a pin 160 carried by the plunger. The position of the notches 155 will, of course, vary in accordance with the angle of the thread to be cut. If a United States standard thread is being cut, in which instance the faces of the thread are at an angle of 60° and the thread is truncated, the notches 155 will be three in number and spaced 60° apart. Of course, the same segmental plate can have two or more series of corresponding notches to make it usable in connection with threads of varying types or sizes. When the parts are in the position shown in Fig. 12, the diamond point is in position to resurface the truncated part of the wheel and when the carriage is in the position shown in dotted lines in Fig. 12, the diamond point is in position to resurface one side face of the wheel. If the carriage were thrown to its extreme opposite position, the diamond point would be in position to resurface the other side face of the wheel.

During the resurfacing operation, the center about which the resurfacing tool is indexed, i. e., a point lying in the axis of the shaft 137, is in a plane passing through the center of the edge of the grinding wheel. It is evident that because of the roughness of the grinding wheel and extremely fine adjustments required to give the grinding edge thereof the precise shape of the thread, it is practically impossible to properly true the wheel by using a separate resurfacing tool for each face of the wheel or employing a single resurfacing tool requiring a separate setting for each face. Certainly such arrangements would require the greatest care and patience on the part of the operator and necessitate a great waste of time without any assurance that the grinding wheel as resurfaced was absolutely true. This is particularly true when a truncated thread is to be ground, for the flat of the thread has a definite relation to the pitch, under the United States standard it being one-eighth of the pitch, and it is obvious that after the two side faces of a grinding wheel were resurfaced there would be the greatest difficulty in then so adjusting the resurfacing tool that the flat would be of the precise size required.

With the truing device herein described

the objections to the arrangements just noted are entirely eliminated for, as the diamond point is indexable about a fixed axis, a single diamond point may be used and a single setting, which may be obtained with the gauge hereinafter described, is necessary to resurface both faces of the grinding wheel where a V-shaped thread is cut, and all three faces of the wheel where a truncated thread is to be ground, with the assurance that in the latter case the flat will have the proper size in relation to the pitch of the thread.

It is, of course, evident that during the final resurfacing operation the wheel has a fixed relation to the center about which the diamond point is indexed, which center is in the plane of the center of the edge of the wheel and consequently the angular disposition of the side faces will accord with the angular disposition of the thread which is being cut depending upon what type of thread it is. If it is a United States standard, the side walls of the thread are at an angle of 60° and consequently the side cutting faces of the wheel will be disposed at an angle of 60° to one another, for the reason that the carriage is so indexed and, furthermore, this angle will, at all times and no matter to what extent the wheel is resurfaced or resharpened, be bisected by the center line of the wheel edge. When the diamond point is indexed to mid-position for resurfacing the flat or truncated part of the wheel, and because of the fixed relation of the wheel to the center about which the carriage is indexed and the fixed relation of the diamond point to that center, the extent of truncation will be correct.

For the purpose of making certain that the extent of the flat of the wheel shall be correct for any given pitch of thread, a gauge is provided for setting the diamond point so far as its longitudinal adjustment in the arm 141 is concerned. This gauge comprises a pivoted arm 165, mounted on the arm 141, which can be thrown over in front of the diamond point position, as indicated in dotted lines in Fig. 13, and the end of this pivoted member is threaded to receive gauge plugs 166. A gauge plug will be provided to correspond to the various thread pitches. It will be seen that the gauge arm 165 has a fixed or definite relation to the tool carrying part or arm 141 in that it is pivoted for swinging movement only thereon, and as the arm 141 is fixed against longitudinal movement on the shaft 140 it has a definite relation to the axis about which the carriage is indexed. It, therefore, follows that by screwing home a gauge plug of proper length into the gauge arm and then bringing the diamond point into engagement with the end of this plug, the diamond point

is properly adjusted relative to the fixed axis about which it is indexed. That gauge plug is selected which corresponds to the pitch of the thread which is being operated on, it is 5 screwed home into the member 165, thrown down in front of the diamond point and the diamond point is moved through the arm 141 until it touches the end of this plug, when it is clamped into position. The gauge 10 is then thrown back out of position, as shown in full lines in Fig. 13. By indexing the carriage, the active faces of the wheel are roughed out to substantially final form, the wheel being fed up to the diamond point 15 for this purpose and then fastened in position so that its relation to the indexible carriage is fixed. Then by taking a final cut on all three faces of the wheel, the side faces will be properly shaped and properly sized 20 and at the proper angular relation with respect to one another and the flat will be accurately finished to correspond in extent to precisely what it should be for the pitch of the thread being cut.

25 As has heretofore been stated, when a thread is being operated on, the wheel must have an angular adjustment corresponding to the lead of the thread. To properly shape the edge of the grinding tool so that it will 30 correspond to the shape of the tooth it is necessary that the resurfacing or reshaping operation be carried out on a line lying in a plane which includes the axis of the work and the line about which the wheel is angularly adjustable, this latter line, as previously stated, being the line $a-a$ of Fig. 5. In the present instance, the diamond point is diametrically opposite to the point of contact of the work and the tool, and when the 35 diamond point is indexed, and also when it is reciprocated for resurfacing, it moves in the plane which includes the line $a-a$ and the axis of the work. It is obvious that the grinding faces of the wheel have a line contact with the corresponding faces of the thread operated upon, and the plane in which this line of contact lies is a plane in which the diamond point is indexed. Thus 40 it will be seen that the angular adjustment of the grinding wheel is not disturbed in any particular during the resurfacing operation. As the diamond point oscillates about the axis of the shaft 140, it moves slightly out of a horizontal plane but for practical purposes the arc of movement is so small as 45 to be negligible.

Since the bracket 135 upon which the truing device is carried, though adjustable, is for practical purposes fixed to the pedestal 50 a of the machine, and as the grinding wheel is also mounted on this base and movable only in a direction at right angles to the axis of work to and from the truing device, the alignment of the truing device and the wheel 55 is never changed. Thus, the wheel may be

resurfaced as many times as may be necessary and it is always certain that when it is brought back into contact with the work its shape and relationship thereto is unchanged 70

The truing device is in fixed relation to the work gauge after the latter has been adjusted to a piece of work and fixed in position, it being remembered that by this adjustment the work gauge is brought into 75 fixed relation with the wheel. Consequently, these three parts, the work gauge, the wheel and the truing device, being once set for a piece of work of a given character, always remain so set with relation to one another 80 for other work of like character.

In describing the invention herein illustrated the conventional terms have been used but it is to be understood that they have been used solely for the purpose of description and they are not to be taken as having any limiting effect. For instance, in certain of the claims the tool which operates upon the work is recited as a grinding wheel but this terminology has been employed solely for 90 the purpose of convenience and to avoid confusion, it being obvious that a tool of other kind or character may be utilized in the combinations recited.

What I claim is:—

1. In a machine of the character described, and in combination, a fixed bed, a grinding wheel thereon, a rocking bed fulcrumed on said fixed bed, a work holder slidably mounted on said rocking bed and having 100 means for rotatably supporting a piece of work, and automatically operated means for rocking said bed.

2. In a machine of the character described, and in combination, a fixed bed, a grinding wheel thereon, a rocking bed fulcrumed on said fixed bed, a work holder slidably mounted on said rocking bed for movement on a line parallel to the axis on which said rocking bed swings, said work holder including means for rotatably supporting a piece of work on an axis substantially parallel to the direction of movement of said work holder, and automatically operated means for rocking said bed.

3. In a machine of the character described, a fixed bed, knife edges thereon, a tool on said fixed bed, a rocking bed fulcrumed on said knife edges, a work holder mounted for reciprocation on said rocking bed and including a work spindle, means for reciprocating said work holder, and means for rocking said rocking bed.

4. In a machine of the character described, a fixed bed, knife edges thereon, a grinding wheel on said fixed bed, a rocking bed fulcrumed on said knife edges, a work holder slidably mounted on said rocking bed and provided with a work spindle, a lead screw 125 on said rocking bed for moving said work 130

- holder, means on said rocking bed for rocking the same, and mechanism on said rocking bed for driving said spindle, lead screw and rocking means.
5. In a machine of the character described, a fixed bed, a tool thereon, a rocking bed fulcrumed on said fixed bed, a work holder mounted on said rocking bed for sliding movement parallel to the axis about which
- 10 said rocking bed swings and including means for rotatably supporting a piece of work, and automatically operated means for rocking said bed to feed the work relative to said tool.
- 15 6. In a machine of the character described, and in combination, a fixed bed, a grinding wheel thereon, fulcrums on said fixed bed, a rocking bed mounted on said fulcrums against movement other than a rocking one,
- 20 a work holder slidably mounted on said rocking bed and including a work spindle for rotatably supporting a piece of work, and automatically operated means for rocking said rocking bed together with the work holder thereon.
- 25 7. In a machine of the character described, and in combination, a fixed bed, a grinding wheel thereon, a rocking bed fulcrumed on said fixed bed, a work holder mounted on said rocking bed for sliding movement and including a work spindle, a lead screw on said rocking bed for moving said work holder, means on said rocking bed for driving said spindle and lead screw, and automatically operated means carried by said rocking bed for rocking the same.
- 30 8. In a machine of the character described, a fixed bed, a rocking bed supported thereon, a tool on said fixed bed, a work holder on the
- 35 rocking bed including means for rotatably supporting a piece of work, and automatically operated feeding means carried by said rocking bed and including a variable connection resting upon said fixed bed, said
- 40 rocking bed being movable relative to said variable connection.
- 45 9. In a machine of the character described, a fixed bed, a rocking bed thereon, a tool on one of said beds, a work holder on the other of said beds, feeding means including a variable connection comprising a rotatable nut carried by and having longitudinal movement on said rocking bed, and a screw in threaded engagement with said nut and resting on said fixed bed.
- 50 10. In a machine of the character described, a fixed bed, a rocking bed, a tool on one of said beds, a work holder on the other of said beds, a rocking beam pivoted on said
- 55 rocking bed, and means associated with said rocking beam for rocking said rocking bed.
- 60 11. In a machine of the character described, a fixed bed, a rocking bed, a tool on one of said beds, a work holder on the other of said beds, a rocking beam pivoted
- 65 on said rocking bed, and a feed mechanism having an adjustable point on which said rocking beam is fulcrumed.
12. In a machine of the character described, a fixed bed, a tool thereon, a rocking bed, a work holder thereon, a rocking beam pivoted on said rocking bed, and a feed mechanism having a variable connection on which one end of said rocking beam rests, said rocking bed being movable relative to said variable connection to permit said rocking beam to be rocked about said variable connection as a fulcrum.
13. In a machine of the character described, a fixed bed, a tool thereon, a rocking bed supported on said fixed bed, a sliding work holder thereon, and lifting means for raising the bed to withdraw the work from the tool on the reverse stroke of said work holder.
14. In a machine of the character described, a fixed bed, a tool thereon, a rocking bed, a sliding work holder thereon, and a cam carried by said rocking bed and cooperating with a fixed abutment for lifting said rocking bed on the reverse stroke of said work holder.
15. In a machine of the character described, a fixed bed, a tool thereon, a rocking bed, a work holder thereon, and means for lifting said rocking bed on the reverse stroke of said work holder controlled by the movement of said holder.
16. In a machine of the character described, a fixed bed, a grinding wheel fixed thereon, a rocking bed fulcrumed on said fixed bed, a reciprocable work holder on said rocking bed including a work spindle, and means for swinging said rocking bed to withdraw the work from the tool on the reverse stroke of said work holder.
17. In a machine of the character described, a fixed bed, a tool thereon, a rocking bed, a work holder thereon, feeding means on said rocking bed, and means for lifting said rocking bed on the reverse stroke of said work holder, both of said means being controlled by movement of said holder.
18. In a machine of the character described, a fixed bed, a rocking bed, a tool on one of said beds, a work holder on the other of said beds, a rocking beam pivoted on said rocking bed, and a plurality of means cooperating with said rocking beam for rocking said rocking bed.
19. In a machine of the character described, a fixed bed, a rocking bed, a tool on one of said beds, a work holder on the other of said beds, a rocking beam pivoted on said rocking bed, and a plurality of means cooperating with said rocking beam for rocking said rocking bed, one of said means constituting a fulcrum for said beam when it is acted upon by other of said means.
20. In a machine of the character de-

- scribed, a fixed bed, a rocking bed, a tool on one of said beds, a work holder on the other of said beds, a rocking beam pivoted on said rocking bed, a feed mechanism having a variable connection between said fixed bed and said rocking beam, and means carried by said rocking bed and acting upon said rocking beam to swing the latter about said variable connection as a fulcrum.
21. In a machine of the character described, a fixed bed, a rocking bed, a tool on one of said beds, a work holder on the other of said beds, a rocking beam pivoted on said rocking bed, a feed mechanism having an adjustable point on which one end of said rocking beam rests, and a cam acting on the other end of said rocking beam to rock the same about said adjustable point as a fulcrum.
22. In a machine of the character described, a fixed bed, a rocking bed, a tool on one of said beds, a work holder on the other of said beds, a rocking beam pivoted on said rocking bed, a feed mechanism having a variable connection between one end of said rocking beam and said fixed bed, and a lifting cam acting upon the other end of said rocking beam.
23. In a machine of the character described, a fixed bed, a rocking bed, a tool on said fixed bed, a work holder slidably mounted on said rocking bed, and a pattern disk on said rocking bed for imparting a rocking movement to said rocking bed corresponding to the contour of the work.
24. In a machine of the character described, a fixed bed, a rocking bed, a tool on one of said beds, a work holder on the other of said beds, a rocking beam pivoted on said rocking bed, feeding means including a part upon which said rocking beam rests, and a pattern disc carried by said rocking bed and acting on said rocking beam to swing the same about said part of said feeding means as a fulcrum and thus rock the rocking bed.
25. In a machine of the character described, a fixed bed, a rocking bed, a tool on one of said beds, a work holder on the other of said beds, a rocking beam pivoted on said rocking bed, a feeding means, lifting means and a pattern disc cooperating with said rocking beam to rock said rocking bed, said feeding means having a point constituting the fulcrum for the rocking beam when the latter is acted upon by said lifting means or pattern disc.
26. In a machine of the character described, a fixed bed, a rocking bed, a tool on one of said beds, a work holder on the other of said beds, a rocking beam pivoted on said rocking bed, feeding means having a variable point on which one end of said rocking beam rests, and a pattern disc and a lifting cam cooperating with the other end of said rocking beam.
27. In a machine of the character described, a fixed bed, a tool thereon, a rocking bed, a work holder thereon, a lead screw for said work holder, lifting means for said rocking bed, and means controlled by the movement of said work holder for reversing said screw and actuating said lifting means.
28. In a machine of the character described, a fixed bed, a tool thereon, a rocking bed, a work holder thereon, a lead screw for said work holder, a lifting cam for said rocking bed, a clutch for intermittently rotating said cam and controlled by movement of said work holder, and a reverse clutch for said lead screw actuated through said first clutch.
29. In a machine of the character described, a fixed bed, a tool thereon, a rocking bed, a work holder thereon, a lead screw for said work holder, feeding means for said bed to move the work relative to said tool, lifting means for raising the bed on the reverse stroke of said work holder, and means actuated by said work holder and controlling said lead screw, feeding means, and lifting means.
30. In combination, an intermittently rotatable cam having a groove with an offset portion, and a clutch mechanism including a shipper having a pin working in the groove of said cam, said pin being engageable in said offset portion of said cam groove to place said clutch mechanism in neutral position.
31. An escapement clutch mechanism including a rotatable part, a pivoted pawl thereon, a constantly rotating ratchet wheel with which said part cooperates, a pair of pivoted escapement levers adapted to be moved into and out of the path of said pawl, a longitudinally movable rod having opposed abutments, and spring actuated means for maintaining one end of each of said escapement levers against said abutments.
32. In a machine of the character described, a rocking bed, a work holder thereon, a lead screw therefor, a lifting cam for raising the work during the reverse stroke of said work holder, a clutch for intermittently rotating said cam and controlled by the movement of said holder, a reverse clutch for said lead screw actuated through said first clutch, and manually operable means associated with said first clutch for disengaging the same at a predetermined time to stop the machine.
33. In a machine of the character described, a fixed bed, a tool fixed thereon, a bed movable to and from said tool but fixed against lateral movement relative thereto,

- a sliding work holder on said movable bed, and a work gauge adjustably carried by said movable bed.
34. In a machine of the character described, a fixed bed, a tool fixed thereon, a bed movable to and from said tool but fixed against lateral movement relative thereto, a sliding work holder on said movable bed, a work gauge adjustably carried by said movable bed, and means for moving said holder to set the work to said gauge.
35. In a machine of the character described, a fixed bed, a tool fixed thereon, a rocking bed on said fixed bed, a sliding work holder thereon, and a work gauge adjustably carried by said rocking bed and having, after adjustment, fixed relation to said tool.
36. In a machine of the character described, a fixed bed, a tool thereon, a rocking bed, a sliding work holder on said rocking bed, a bracket fixed on said rocking bed, and a work gauge pivotally and adjustably carried by said bracket.
37. In a machine of the character described, a fixed bed, a grinding wheel thereon, a bed movable to and from said grinding wheel but fixed against lateral movement relative thereto, a reciprocable work holder on said movable bed and including means for rotatably supporting a piece of work, and a work gauge adjustably carried by said movable bed.
38. In a thread finishing machine, means for adjusting a gauge into predetermined relation to a grinding wheel and means for adjusting the partially formed thread to the gauge and thereby into proper relation to the grinding wheel.
39. A method of finishing a screw thread which consists in setting a gauge into predetermined relation to a grinding wheel and then adjusting the partially formed thread to the gauge without disturbing the relation of the wheel and gauge.
40. In a thread finishing machine, means for adjusting a gauge into predetermined relation to a grinding wheel having an edge corresponding to the groove of the thread to be finished, means for adjusting the partially finished thread to the gauge, and means for resurfacing the grinding wheel without disturbing the relation between the grinding wheel and gauge.
41. In a thread finishing machine, means for adjusting a gauge into predetermined relation to a grinding wheel, means for adjusting the partially formed thread to the gauge and means for moving the work after it is adjusted to the gauge in a fixed path independently of said gauge.
42. The method of finishing a circumferentially contoured surface which consists in forming on a test piece a surface similar to that of the work, setting a gauge to the test piece without disturbing the relation of the test piece and tool, fixing the gauge in position, substituting the work for the test piece, and then setting the partially finished work to the gauge without disturbing the relation of the gauge and tool.
43. In a machine of the character described, and in combination, a fixed bed, a grinding wheel fixed thereon for rotation, a rocking bed fulcrumed on said fixed bed, a work holder slidably mounted on said rocking bed and including a work spindle, a lead screw on said rocking bed for moving said work holder, means for rocking said bed, and mechanism on said rocking bed for driving and controlling the movements of said work spindle, lead screw and rocking means.
44. In a machine of the character described, a fixed bed, a grinding wheel fixed thereon, a rocking bed fulcrumed on said fixed bed, a work holder slidably mounted on said rocking bed and having means for rotatably supporting a piece of work, and a plurality of automatically operated means for rocking said bed.
45. In a machine of the character described, a fixed bed, a grinding wheel fixed thereon, a rocking bed fulcrumed on said fixed bed, a work holder slidably mounted on said rocking bed and having means for rotatably supporting a piece of work, and a plurality of means on said rocking bed for rocking said bed to relatively move said wheel and work towards and away from each other.
46. In a machine of the character described, a fixed bed, a tool thereon, a rocking bed, a slideable work holder thereon, automatically operated means for rocking said rocking bed to relatively feed the work and tool, and means for lifting said rocking bed on the reverse stroke of said work holder whereby the tool clears the work.
47. In a machine of the character described, a fixed bed, a rocking bed fulcrumed thereon, a tool on one of said beds, a slideable work holder on the other of said beds including means for rotatably supporting a piece of work, means for reciprocating said work holder to thereby move the same on its operative and return strokes, means for periodically rocking said bed to feed the work relative to the tool, and means for lifting said rocking bed and maintaining it in raised position on the reverse stroke of said holder whereby the tool clears the work.
48. In a machine of the character described, a fixed bed, a grinding wheel fixed for rotation thereon, a rocking bed fulcrumed on said fixed bed, a reciprocable work holder mounted on said rocking bed

and including means for rotatably supporting a piece of work, means for periodically rocking said bed to relatively feed the work and wheel, and means for lifting said rocking bed on the reverse stroke of said work holder so that the wheel clears the work.

49. In a machine of the character described, a fixed bed, a tool thereon, a rocking bed fulcrumed on said fixed bed, a reciprocable work holder mounted on said rocking bed and including a work spindle, a lead screw carried by said rocking bed for reciprocating said work holder, means for rocking said rocking bed to feed the work relative to the tool, means on said rocking bed for lifting the same on the reverse stroke of said work holder, and mechanism on said rocking bed for driving and controlling said work spindle, lead screw, feeding means and lifting means.

50. In a machine of the character described, a fixed bed, a tool thereon, a rocking bed fulcrumed on said fixed bed, a reciprocable work holder thereon provided with means for rotatably supporting a piece of work, means for swinging said bed during the cutting operation to effect a predetermined contour on the work, and additional means for lifting said rocking bed on the reverse stroke of said work holder.

51. In a machine of the character described, a fixed bed, a grinding wheel fixed thereon for rotation, a rocking bed fulcrumed on said fixed bed, a reciprocable work holder mounted on said rocking bed and including a work spindle, a lead screw carried by said rocking bed for reciprocating said work holder, means for swinging said rocking bed during the cutting operation to effect a predetermined contour on the work, means for lifting said rocking bed on the reverse stroke of said work holder whereby the tool clears the work, and mechanism on said rocking bed for driving and controlling said work spindle, lead screw, contouring means and lifting means.

52. In a machine of the character described, a fixed bed, a tool thereon, a rocking bed fulcrumed on said fixed bed, a reciprocable work holder on said rocking bed provided with means for rotatably supporting a piece of work, means for periodically swinging said rocking bed to feed the work relative to the tool, and means for rocking said bed during the cutting operation to effect a predetermined contour on the work.

53. In a machine of the character described, a fixed bed, a grinding wheel thereon, a rocking bed fulcrumed on said fixed bed, a reciprocable work holder on said rocking bed provided with a work spindle for rotatably supporting a piece of work, means for periodically swinging said rocking bed to feed the work relative to the tool, means for rocking said bed during the cutting oper-

ation to effect a predetermined contour on the work, and mechanism on said rocking bed for driving and controlling said work spindle, feeding means and contouring means.

54. In a machine of the character described, a fixed bed, a tool thereon, a rocking bed fulcrumed on said fixed bed, a reciprocable work holder slidably mounted on said rocking bed and including means for rotatably supporting a piece of work, means for rocking said bed to periodically feed the work relative to the tool, means for rocking said bed during the cutting operation to effect a predetermined contour on the work, and means for lifting said rocking bed on the reverse stroke of said work holder.

55. In a machine of the character described, a fixed bed, a grinding wheel thereon, a rocking bed fulcrumed on said fixed bed, a reciprocable work holder mounted on said rocking bed and including a work spindle, a lead screw carried by said rocking bed for reciprocating said work holder, means for rocking said bed to periodically feed the work relative to the tool, means for rocking said bed during the cutting operation to effect a predetermined contour on the work, means for lifting said rocking bed on the reverse stroke of the work, and mechanism on the rocking bed for driving and controlling the movements of said work spindle, lead screw and all of said rocking means.

56. In a machine of the character described, a fixed bed, a tool thereon, a rocking bed fulcrumed on said fixed bed, a slideable work holder on said rocking bed provided with a work spindle, a lead screw for reciprocating said work spindle, a rocking beam pivoted on said rocking bed, a plurality of means cooperating with said rocking beam for rocking said rocking bed, and mechanism on said rocking bed for driving and controlling said lead screw, work spindle and rocking means.

57. In a machine of the character described, a fixed bed, a rocking bed, a tool on one of said beds, a work holder on the other of said beds, a rocking beam pivoted on said rocking bed, means cooperating with said rocking beam to rock said bed to effect a predetermined contour on the work, and means cooperating with said rocking beam for rocking said bed to relatively feed the tool and the work.

58. In a machine of the character described, a fixed bed, a rocking bed, a tool on one of said beds, a work holder on the other of said beds, a rocking beam pivoted on said rocking bed, means cooperating with said rocking beam for rocking said bed to relatively feed the tool and the work, and means cooperating with said rocking beam for lifting said rocking bed and thereby move the

work and tool away from each other on the reverse stroke.

59. In a machine of the character described, a fixed bed, a rocking bed, a tool on one of said beds, a work holder on the other of said beds, a rocking beam pivoted on said rocking bed, means cooperating with said rocking beam for rocking said rocking bed to effect a predetermined contour on the work, and means cooperating with said rocking beam for rocking said bed and thereby move the work and tool out of engagement on the reverse stroke of the work.

60. In a machine of the character described, a fixed bed, a rocking bed, a tool on one of said beds, a work holder on the other of said beds, a rocking beam pivoted on said rocking bed, means cooperating with said rocking beam for rocking said bed to effect feeding of the work, means cooperating with said rocking beam for lifting said rocking bed thereby moving the work away from the tool on the reverse stroke of the work, and means cooperating with said rocking beam for rocking the bed to effect a predetermined contour on the work.

61. In a machine of the character described, a fixed bed, a rocking bed, a tool on one of said beds, a work holder on the other of said beds, a rocking beam pivoted on said rocking bed; and feeding means, lifting means and contouring means cooperating with said rocking beam to rock said rocking bed, one of said means constituting the fulcrum for the rocking beam when the latter is acted upon by other of said means.

62. In a machine of the character described, a fixed bed, a tool thereon, a work holder mounted for longitudinal and transverse movements relative to said tool and including means for rotatably supporting a piece of work, means for longitudinally moving said work holder at a cutting speed on its operative stroke and quickly returning said work holder on its inoperative stroke, means for moving said work holder away from said tool on the return stroke of said work holder whereby the tool clears the work on said stroke, and means for transversely moving said work holder during the cutting operation to effect a predetermined contour on the work, said last mentioned means being ineffectual during the return stroke of the work whereby chattering between said means and the part on which it operates is obviated.

63. In a machine of the character described, a fixed bed, a tool thereon, a work holder mounted for longitudinal and transverse movements relative to said tool and including means for rotatably supporting a piece of work, means for moving said work holder at a cutting speed on its operative stroke, a cam for moving said work holder transversely during the cutting operation to ef-

fect a predetermined contour on the work, and means for moving said work holder away from said tool so that the tool clears the work on the return stroke of the latter, said cam being separated from the part on which it operates on the reverse stroke of the work whereby chattering is obviated.

64. In a machine of the character described, a fixed bed, a tool thereon, a work holder mounted for longitudinal and transverse movements relative to said tool and including a work spindle, a lead screw for moving said work holder at a cutting speed on its operative stroke and at a fast speed on its inoperative stroke, a cam for moving said work holder transversely back and forth to effect a predetermined contour on the work, means for driving said spindle and cam on both strokes of said work holder, and a cam for transversely moving said work holder on the inoperative stroke thereof to separate the tool from the work and also separate said first cam from the part on which it operates whereby chattering is obviated.

65. In a machine of the character described, a fixed bed, a tool thereon, a work holder mounted for longitudinal and transverse movements relative to said tool, a rocking beam associated with said work holder, means associated with said rocking beam for moving said work holder away from said tool on the return stroke of the work, and a cam acting on said rocking beam to move said work holder transversely and thereby effect a predetermined contour on the work, said rocking beam being disengaged from said cam when said means moves the work holder away from said tool.

66. In a machine of the character described, a fixed bed, a tool thereon, a rocking bed, a slidable work holder on said rocking bed provided with means for rotatably supporting a piece of work, means for reciprocating said work holder, means for moving said work holder away from said tool on the return stroke of said work holder whereby the tool clears the work, and means for rocking said rocking bed during the cutting stroke to effect a predetermined contour on the work, said last mentioned means being ineffectual during the return stroke of the work whereby chattering is obviated.

67. In a machine of the character described, a fixed bed, a tool thereon, a rocking bed, a work holder slidably mounted thereon and including means for rotatably supporting a piece of work, means for moving said work holder at a cutting speed on its operative stroke and quickly returning it on its inoperative stroke, a cam for rocking said bed during the cutting operation to effect a predetermined contour on the work, and means for rocking the bed to move the work away from the tool on the reverse

- stroke of said work holder, said cam being separated from the part on which it operates on the reverse stroke of the work whereby chattering is obviated.
- 5 68. In a machine of the character described, a fixed bed, a tool thereon, a rocking bed, a slideable work holder on said rocking bed including a work spindle, means for reciprocating said work holder, a rocking beam pivoted on said rocking bed, means for lifting said rocking bed on the reverse stroke of the work whereby said tool clears the work, and a cam cooperating with said rocking beam for rocking said bed during the cutting operation to effect a predetermined contour on the work, said cam being separated from said rocking beam on the reverse stroke of the work whereby chattering is obviated.
- 10 69. In a machine of the character described, a fixed bed, a tool thereon, a rocking bed, a slideable work holder thereon provided with a work spindle, means for reciprocating said work holder, a rocking beam pivoted on said rocking bed, a cam acting on said beam for rocking said rocking bed to effect a predetermined contour on the work, and a cam acting on said rocking beam to lift said rocking bed and thereby separate the tool from the work on the reverse stroke of the latter and also raise said rocking beam from said first cam.
- 15 70. In a machine of the character described, a fixed bed, a tool thereon, a rocking bed, a slideable work holder on said rocking bed provided with a work spindle, means for reciprocating said work holder, means carried by said rocking bed for rocking the same to move the work from the tool on the reverse stroke of said work holder, and a cam carried by said rocking bed for rocking the same to effect a predetermined contour on the work, said cam being ineffectual during the return stroke of said work holder whereby chattering is obviated.
- 20 71. In a machine of the character described, a fixed bed, a tool thereon, a rocking bed, a slideable work holder on said rocking bed including a work spindle, means for reciprocating said work holder, a rocking beam pivoted on said rocking bed, means carried by said rocking bed for lifting said rocking bed on the reverse stroke of the work whereby said tool clears the work, and a cam carried by said rocking bed and cooperating with said rocking beam for rocking said bed during the cutting operation to effect a predetermined contour on the work, said cam being separated from said rocking beam on the reverse stroke of the work whereby chattering is obviated.
- 25 72. In a machine of the character described, a fixed bed, a grinding wheel thereon, a rocking bed fulcrumed on said fixed
- bed, a work holder mounted for reciprocation on said rocking bed in parallelism with the axis of the latter and including means for rotatably supporting a piece of work, and a work gauge carried by said rocking bed for adjustment on a line parallel to the axis about which said bed is rocked, said gauge having, after adjustment, fixed relation to said grinding wheel.
- 30 73. In a machine of the character described, a fixed bed, a tool thereon, a rocking bed fulcrumed on said fixed bed, a slideable work holder on said rocking bed and including a work spindle, a lead screw for said work holder, means for rocking said bed, driving mechanism carried by said rocking bed for said lead screw and spindle; and a flexible drive for said mechanism and permitting substantially free rocking movement of said rocking bed.
- 35 74. In a machine of the character described, a fixed bed, a tool thereon, a rocking bed fulcrumed on said fixed bed, a slideable work holder on said rocking bed including a work spindle, a lead screw on said rocking bed for moving said work holder, means on said rocking bed for rocking the same; driving mechanism including gearing mounted on said rocking bed for said lead screw, spindle and rocking means; and a flexible drive belt for said mechanism tending to hold said rocking bed to its fulcrums.
- 40 75. In a machine of the character described, a fixed bed, a tool slide thereon, a tool on said slide, a rocking bed fulcrumed on said fixed bed, a reciprocable work holder on said rocking bed, means for adjusting said tool slide transversely of said work holder, and means operable manually to adjust said rocking bed and operable automatically to feed the work relative to the tool.
- 45 76. A bearing for a knife edge comprising a pair of members fitted together, each having a face forming part of a V-shaped groove between the blocks.
- 50 77. A bearing for a knife edge comprising a pair of plane surfaced blocks fitted together to form a V between two of such plane surfaces.
- 55 78. In combination, a pair of blocks fitted together to form a V-shaped groove therebetween, a bed recessed to receive said blocks, and means for clamping said blocks in said recess.
- 60 79. In combination, a pair of blocks fitted together to form a V-shaped groove therebetween to receive a knife edge, a bed recessed to receive said blocks, and clamping means to hold said blocks firmly in said recess.
- 65 80. In combination, a pair of blocks fitted together and forming a V-shaped groove therebetween to receive a knife edge, a bed recessed to receive said blocks, and clamping plates cooperating with said bed to hold said blocks rigidly in place.

81. In a machine of the character described, a fixed bed, a grinding wheel fixed thereon, a rocking bed fulcrumed on said fixed bed, a work holder mounted for reciprocation on said rocking bed in parallelism with the axis of the latter and including a spindle for rotatably supporting a piece of work, means for reciprocating said work holder, means for driving said last mentioned means in timed relation to said spindle, and a work gauge adjustably mounted on said rocking bed. 10
